MULTIPLE PANE WINDOW UNITS
 David Shinefeld, Oreland, Pa., assignor to Multipane Inc.
 U.S.A., a corporation of Pennsylvania
 Filed Nov. 17, 1965, Ser. No. 508,284
 9 Claims. (Cl. 52—616)

ABSTRACT OF THE DISCLOSURE

Multiple pane window units in which tubular spacers are provided between the panes with pockets in side walls of the spacers for sealing material and sockets in outer walls of the spacers. Clips are provided engaging in the sockets and either with the face of a glass sheet or with another socket.

This invention relates to multiple pane window units, that is to heat insulating window units composed of a plurality of glass sheets separated from each other at their edges by spacers and retained in position by metal clips along their edges.

The principal object of the present invention is to provide improved spacers for multiple pane window units that cushion shock and effectively seal and separate the edges of the window units.

A further object of the present invention is to provide improved retaining and gripping apparatus for multiple pane window units.

A further object of the present invention is to provide improved retaining clips for multiple pane window units that are suitable for use on units with varying numbers of glass sheets.

A further object of the present invention is to provide a structure of the character aforesaid that is simple and inexpensive to manufacture but sturdy and reliable in use.

Other objects and advantageous features of the invention will be apparent from the description and claims.

The nature and characteristic features of the invention will be more readily understood from the following description taken in connection with the accompanying drawing forming part thereof, in which:

FIGURE 1 is a fragmentary front view of a portion of a window unit in accordance with the invention;

FIG. 2 is a view in perspective of a portion of a spacer in accordance with the invention;

FIG. 3 is a vertical sectional view taken on the line 3—3 of FIG. 1;

FIG. 4 is a view similar to FIG. 3 showing a modified form of the invention;

FIG. 5 is a view in perspective showing a corner retaining clip for use with the window unit of the present invention;

FIG. 6 is a view in perspective showing a side retaining clip for use with the window unit of the present invention;

FIG. 7 is a view similar to FIG. 6 showing another form of retaining clip; and

FIG. 8 is a view similar to FIG. 7 showing another form of retaining clip.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings in which a preferred embodiment of the invention is illustrated, the multiple pane window units there shown in-

2

clude a plurality of sheets or panes of glass 8 having opposite side faces 9 and terminal edges 10, held in spaced relationship by spacers 11 and retained together by clips 12.

5 The spacers 11 are preferably formed of sheet metal, but other suitable material can be used, and are of complex shape as shown more particularly in FIGS. 2, 3 and 4. These spacers 11 are initially formed to necessary dimension requirements, and fitted together at the corners 10 so as to form an internally isolated box like perimeter structure along the edges of the panes 8. Each one of the spacers 11 is of generally rectangular shape in cross section as shown in FIGS. 2, 3 and 4.

The structure of the spacers 11 as can be seen particularly in FIGS. 2, 3 and 4, includes a side wall having a flat portion 14 which in assembled position engages a face 9 of one of the sheets of glass 8. An inwardly extending portion 17 of V-shape in cross section is provided contiguous to the lower edge of the portion 14 forming a pocket 15 thereby for the reception of sealing and shock absorbing material 13. A flat wall strip 16 is integrally connected to the V-shaped portion 17.

The wall portion 14 has perpendicular thereto and integral therewith an outer wall portion 18 from which an interiorly disposed wall portion 20 extends to provide a longitudinal socket 21 isolated from the interior and with a throat 21a of lesser width than that of the interior of the socket 21.

The spacer 11 is preferably symmetrical about a central longitudinal plane and has a wall portion 20 forming the other side boundary of the socket 21.

The spacer 11 has another wall portion 18 in coplanar relation to the first mentioned wall portion 18, another wall portion 14 parallel to the first mentioned wall portion 14, an opposite inwardly extending V-shaped portion 17 forming an opposite pocket 15, and another flat wall strip 16 in the same plane as the other wall strip 16. The wall strips 16 have serrated meeting edges 19.

The retaining clips 12 are of various forms to accommodate the desired number of glass sheets 8 used to make a multiple pane unit. The clip 12, as shown in FIG. 5, is a corner clip comprised of flat central strips 23 and 24 at a 90° angle to each other with struck out tongues 26 at the center thereof which extend into the sockets 21. The strips 23 and 24 have bent edge walls 27 fastened thereto and disposed at an acute angle to press inwardly on the faces 9 of the glass sheets 8 with which they engage and retain them in assembled position.

The clip 12a, as shown in FIG. 6 is similar to the clip 12 of FIG. 5 and has a flat central strip 28 which is adapted to be placed along the edges 10 of the sheets 8 as desired and has bent edge walls 29 at acute angles to the central strip 28 to provide a spring action in engagement with faces 9 of the sheets 8. The retention of two sheets 8 of glass in a dual sheet window unit by such clips is shown in FIG. 3.

In order to prevent the accidental disengagement of the clips 12a the tongues 26 can have extending therefrom locking fingers 30 which can be readily entered through the throat 21a by reason of the resilience of the fingers 30 but engage one of the wall portions 20 of the socket 21.

The clip 12b, as shown in FIG. 7, is substantially one half of the clip 12a of FIG. 6 and can be used on the outside sheet of the multiple pane unit when more than two sheets of glass 8 are used. The clip 12b has a central strip 28' with one bent edge wall 27 and with tongues 26 along its other side edge. The tongues 26 preferably have locking fingers 30 as before.

In FIG. 8 another clip 12c is shown which comprises a flat strip 31 with tongues 32 on each side thereof extend-

ing out of the plane of the strip 31 longitudinally spaced as desired. The clip 12c of a width to permit it to bridge one sheet 8 of glass and a full spacer 11 is used to retain the intermediate sheets of glass 8 in assembled position when more than two sheets 8 of glass are used.

The assembled multiple pane unit of FIG. 3 comprises two sheets 8 of glass with a spacer 11 interposed therebetween, sealing material 13 filling the V-shaped indentation 15 and clips 12 and 12b as shown in FIGS. 5 and 6, holding the edges of the glass sheets 8 in assembled relation.

In FIG. 4 a multiple pane unit is illustrated having more than two sheets 8 of glass and utilizes the clips 12b and 12 as shown in FIGS. 7 and 8.

With the foregoing in view the mode of assembly will now be pointed out. The spacers 11 and sheets 8 of glass are cut to suitable size as desired. The spacers 11 are placed between the sheets of glass 8 at their outside edges. The V-shaped pockets 15 are then filled with the shock absorbent adhesive sealing material 13 as desired. The clips 12a are installed over the edges 10 of the glass sheets 8 with the tongues 26 extending into the clip receiving socket 21 and the edge walls 27 pressing on the faces 9 of the glass sheets 8. When a multiple pane unit of more than two sheets 8 of glass is desired the clips 12b and 12c can be used. The clips 12b have one edge wall 27 pressing on the outer face 9 of the outside sheet 8 of glass and the tongue 26 extending into the pocket 21 of the spacer 11. The intermediate sheets 8 of glass are urged together by the clips 12c with tongues 32 extending into the sockets 21 of the spacer 11 bridging a sheet 8 and engaging contiguous spacers 11.

I claim:

1. A multiple pane window unit comprising a plurality of sheets of glass, means for spacing said glass sheets and for sealing the spaces between said glass sheets, said means consisting of tubular members extending between the outer edge portions of the glass sheets, said tubular members each having outer wall portions, opposite side wall portions integral with and extending from said outer wall portion with inwardly disposed portions spaced from said outer wall portions and providing pockets for sealing material, said outer wall portions having walls united in providing a socket therealong accessible along said outer wall portions and isolated from the interior of said tubular member, and inner wall portions integral with said side wall portions and closing the interior of said tubular members, and sealing material in said pockets in engagement with contiguous sheets of glass and said tubular member.
2. A multiple pane window unit as defined in claim 1 in which said tubular members are of sheet metal.
3. A multiple pane window unit as defined in claim 1 in which clip members are provided for holding said sheets and said spacing members in assembled relation, at least one of said clip members having a portion

engaging a face of a glass sheet and a portion in engagement in said socket.

4. A multiple pane window unit as defined in claim 3 in which
- 5 said portion in engagement in said socket is a tongue.
5. A multiple pane window unit as defined in claim 4 in which
- 6 said tongue has a locking finger extending therefrom in engagement in said socket.
- 10 6. A multiple pane window as defined in claim 1 in which
- 7 said socket has a restricted throat portion.
7. A multiple pane window as defined in claim 6 in which
- 15 clip members are provided for holding said sheets and said spacing members in assembled relation, and at least one of said clip members has a portion insertable through said throat portion and into engagement in one of said sockets.
- 20 8. A spacer for multiple pane window units comprising a tubular member having in connected relation, outer wall portions, inner wall portions, and opposite side wall portions integral with and extending between said outer and said inner wall portions, said outer and inner wall portions being aligned and parallel,
- 25 said side wall portions bearing on adjacent surfaces of a pair of coupled panes and having inwardly disposed portions therealong providing pockets for sealing material,
- 30 said outer wall portions having integral walls extending into the tubular member and joined in providing an inwardly disposed socket therealong,
- 35 said socket being isolated by its walls from the interior of the side and inner wall portions of said tubular member.
9. A spacer for multiple pane window units as defined in claim 8 in which
- 40 said wall portions are of sheet metal, and said inner wall portions have meeting edges.
